(74) Attorney, Agent, or Firm — O'BANION & RITCHIEY LLP; John P. O'Banion

(57) **CLAIM**

The ornamental design for a gun sight, as shown and described.

DESCRIPTION

FIG. 1 is a front perspective view of a gun sight showing my new design.

FIG. 2 is a front elevational view thereof.

FIG. 3 is a rear elevational view thereof.

FIG. 4 is a left side elevational view thereof, the right side elevational view being a mirror image of the right side.

FIG. 5 is a top view thereof.

FIG. 6 is a bottom view thereof; and,

FIG. 7 is a front perspective view thereof.

The broken line in FIG. 7 disclose an unclaimed environmental firearm only and form no part of the claimed design.

1 Claim, 3 Drawing Sheets(56)
